UNITED STATES PATENT OFFICE.

JAMES S. THOMPSON, OF PELHAM, NEW YORK.

BRAKE-SHOE MOLD.

Application filed July 20, 1923. Serial No. 652,771.

To all whom it may concern:

Be it known that I, JAMES S. THOMPSON, a citizen of the United States, residing at Pelham, in the county of Westchester and 5 State of New York, have invented certain new and useful Improvements in Brake-Shoe Molds, of which the following is a specification.

This invention relates to the manufacture 10 of brake shoes, and its object is broadly to facilitate the manufacture of brake shoes in permanent molds by providing a mold which can be easily and quickly opened and closed, so that the casting operation can be 15 economically performed.

Another object of the invention which is closely related to the broad general object is to provide a simple means for supporting the attaching lug, the core therefor, and the re- 20 inforcing back for the shoe in the mold cavity, preliminary to the casting operation, so that they will be properly positioned with relation to the shoe body.

And a still further object of the invention 25 is to enable the assembly of the attaching lug, the core therefor and the reinforcing back as a unit so that it can be handled without danger of disarrangement, and eas- 30 ily inserted in its proper position in the mold cavity, to be held therein by the con- 35 formation of the mold cavity and without the necessity of employing any external means.

In the accompanying drawings illustrat- 35 ing selected embodiments of the invention—

Fig. 1 is a central sectional view on the line 1—1 of Fig. 2.

Fig. 2 shows the mold of Fig. 1 partly in elevation and partly in longitudinal sec- 40 tion.

Fig. 3 is a horizontal sectional view on the line 3—3 of Fig. 2.

Fig. 4 is a perspective view showing a portion of the drag in section, and one mem- 45 ber of the cope in elevation.

Fig. 5 is a transverse sectional view cor- 50 responding to Fig. 1, but showing a slightly modified construction.

Referring to the drawings, the mold com- 50 prises a hinged bottom member 6, a rela- 55 tively fixed upper member 7, and a slidable upper member 8. The hinged lower member 6 corresponds with the usual drag and the two upper members 7 and 8 correspond with 60 the usual cope, and I will use this form of description in referring to these parts. The

drag member 6 is hinged at 9 to swing freely down from the cope members 7, 8, and to this end it may be provided with lugs 9 to be engaged by a hinged bar 10 with lugs 60 11 on the relatively stationary member 7. The cope member 8 is slidable relatively to the fixed member 7 and the drag member 6, and it is provided with ears 12 which are bored to receive the guide rods 13 support- 65 ed on the fixed member 7. The drag mem- 70 ber 6 is provided with one or more tongues 14 projecting forward to engage keepers 15 mounted on the slidable member 8. Pins 16 are removably engaged with the keepers 15 70 to cooperate with the tongues 14 for holding the bottom or drag member 6 in operative 75 position. This can be accomplished with- 80 out removing the pins 16 by swinging the drag member up to its operative position and then pushing the sliding member into its operative position, during which latter movement the keepers will engage the tongues; but the pins may be removed and the sliding member pushed into operative 80 85 position and then the drag member swung up to its operative position, after which the pins will be inserted to hold the drag mem- 90 ber in place.

I also prefer to provide one or more 85 clamping bars 17 for securing the members 7 and 8 of the cope together during the cast- 90 ing operation. These bars may be conven- 95 iently pivoted at 18 to the fixed member 7 and provided with hooked ends 19 carrying set screws 20, whereby they may be easily adjusted and secured in place. When the mold is closed the two members of the cope will be held rigidly clamped together, and the drag member will be held rigid in its 95 proper relation to the cope. It will be ob- 100 served that the means for assembling and locking the members of the mold in position for casting, and for releasing the mem- 105 bers to open the mold, are of simple char- 110 acter, easily manipulated and of a substan- tial and efficient construction.

The mold cavity 21 is formed in the cope and this is possible because the cope is made in two members, 7 and 8, one of which is 105 slidable relative to the other to permit the removal of the casting easily from the fixed member. I prefer to recess the top wall of the drag member slightly to form the bot- 110 tom wall of the mold cavity, because the edges of the brake shoe at the wearing face are preferably rounded, and a better joint

can be made between the bottom wall and the side walls of the mold cavity in this way, but this recessing of the drag member would not be necessary if the casting had 5 square edges and the top wall of the drag could be made flush. The drag and cope members are made of metal, and if it is desired to produce a brake shoe with chilled ends and comparatively soft intermediate 10 portion, the drag will be provided with a refractory section 23, and the cope will be provided with refractory sections 24, 25 in the mold cavity walls, so that the metal drag and the metal cope may produce chilled areas 15 at the ends of the shoe while those portions of the shoe opposite the refractory sections will be protected from chilling. The refractory material may be supplied in the form of a refractory coating instead of in the form of 20 inserted sections, as shown, and changes may be made in the form, location and construction of the refractory material to accommodate shoes of different types and sizes and to produce other integral composite structures. 25

Each of the members 7 and 8 constitutes a longitudinal section of the mold, and in the face of each member a portion of the mold cavity is formed. In the particular 30 construction illustrated in Figs. 1-4, about one-half of the mold cavity is formed in each of the cope members 7 and 8, whereas in the construction of Fig. 5 a little more than one-half of the mold cavity is formed 35 in the cope section 7 than in the cope section 8. The mold cavity comprises a space in the scope for the accommodation of the steel attaching lug and the core to form the opening therethrough, and this space comprises the recess 26 for the lug 27 and the lateral extensions 28 of said recess 26 for 40 the ends of the core 29. One-half or thereabouts of the recess 26 and its extensions 28 is located in the face of the cope section 45 7 and the other half or thereabouts is located in the face of the cope section 8, and this enables the unit comprising the steel lug 27, the lug core 29 and the reinforcing back 30 to be assembled with the mold 50 members by placing it in that portion of the recess 26 and its extensions formed in the cope member 7, where it will be supported while the other members of the mold 55 are being adjusted to close the mold. The ends of the lug core 29 are preferably shouldered at 31 to engage complementary shoulders 32 in the cope members. When the steel lug, lug core and reinforcing back as a unit are inserted in the cope member 60 7, it will be supported by the ends of the lug core resting in the half of the recess extensions 28 in the cope member 7, the shoulders of the core resting upon the shoulders of the cope member, to support said unit while the other members of the mold 65

are being adjusted and closed. The recess 26 is preferably somewhat larger than the lug 27 so that the cast metal may flow up around and over the lug 27, as will be clearly understood from Figs. 1 and 2, but this may be changed if it is not desired to have the metal flow over or around the lug. 70

To hold the reinforcing back in its proper relation with the lug and the lug core, I prefer to tie the back to the core by wires 75 33, which, in the embodiment illustrated, pass around the back and the core on opposite sides of the lug and are twisted together to secure the parts against relative movement. This simple arrangement enables the lug, the lug core and the reinforcing back to be assembled and united in a unit which can be easily handled and inserted in the mold, and which will insure proper positioning of the parts in the shoe casting. If the wires are not destroyed in the casting operation, any projecting parts thereof can be easily removed after the shoe has been discharged from the mold. By supporting the reinforcing back in the mold 80 cavity in the manner described, the operation of preparing the mold for the cast is greatly facilitated and I am enabled to dispense with the provision of wires extending through the cope to be fastened to the back after the latter is placed in the mold cavity. The present invention increases the speed of assembling the mold for casting operation and better insures accuracy in the 85 positioning of the lug and the reinforcing back in the shoe. 90

It is only necessary to provide soft sand vents 34 in the mold to permit the escape of gases. I prefer to locate the wires 33 close to the lug 27 where they will engage the reinforcing back 30 at its recessed central part 35. 95

My invention provides a permanent mold of simple construction which can be easily handled for rapidly and economically casting brake shoes, and for producing brake shoes of uniform and superior quality. The construction shown is adapted for casting an approved type of car shoe which is standard on a great many railroads, and which has chilled ends and an intermediate soft cast iron wearing face, but this construction may be varied to produce other types of shoes. The construction of the mold in three members and associating these members in the manner set forth is of special 110 value and importance since it enables the mold to be rapidly handled to make and discharge a casting in fast time. By making the cope in two members, one being relatively fixed and the other relatively slidably, and the drag in one member hinged to swing away from the cope, I have produced a form of mold which I believe is particularly suited for casting brake shoes, 115 120 125 130

which are a comparatively heavy casting. When the casting operation is completed, I prefer to remove the pins 16 and permit the drag to swing downward as indicated in broken lines in Fig. 1. The shoe casting will remain held in the cope, under all ordinary conditions, until the sliding member 8 of the cope is pulled away from the relatively fixed member 7, and if the shoe casting does not then drop out of the fixed member 7 it can be very easily dislocated therefrom. Thus the drag of the mold is protected from injury when the shoe casting is discharged from the mold, and likewise the cope members are supported so that the shoe can be discharged from the cope without injury to its members. This is especially important where the mold cavity is faced with refractory material, because it avoids wear of the refractory facing. The assembly of the lug, its core and the back in a unit is of particular value and importance because these units can be prepared in quantities and inserted in the mold as required, and the units can be handled freely without danger of injuring or disarranging the parts thereof so that the whole operation of placing these parts in the mold cavity and supporting them in proper position for embedment in the body of the shoe casting is greatly facilitated. If it should be desired to have the top of the steel lug bare, instead of being covered with cast iron, the member 7 of the cope may be extended at the top 36 to a position above the lug to be engaged by the lug as indicated in Fig. 5, and in this construction the parting line between the members 7 and 8 of the cope will be offset at 37.

I have illustrated the invention in a selected embodiment which I believe will be readily understood by those skilled in the art, but I do not wish to be restricted to the use of my invention for the manufacture of this particular type of shoe, since it can be used with satisfactory results in the production of other shoes and in making other castings for which my invention may be employed, and therefore I consider myself entitled to make all changes in the form, construction and arrangement of parts as fairly fall within the scope of the following claims.

55 I claim—

1. A permanent mold for making castings, comprising a relatively fixed member, a hinged member, a slidable member, and means for securing said members together to close the mold.

2. A permanent mold for making castings, comprising a relatively fixed member, a member hinged to said fixed member and adapted to swing freely therefrom, a member slidable relative to said fixed member,

and means for holding said members together to close the mold.

3. A permanent mold for making castings, comprising a hinged drag member, a two-member cope, one of said cope members being slidable relative to the other cope member, and means for holding said members together to close the mold. 70

4. A permanent mold for making castings, comprising a two-member cope, one of said cope members being relatively fixed and the other cope member being slidable relatively to the fixed cope member, a drag member hinged to the fixed member to swing freely relative thereto, and means for holding said members together to close the mold. 75 80

5. A permanent mold for making castings, comprising a movable drag member, a two-member cope, each cope member having a part of the mold cavity therein, one of said cope members being relatively fixed and the other cope member being slidably supported on the fixed cope member, and means for holding said members together to close 90 the mold. 85

6. A permanent mold for making castings, comprising a two-member cope, one of said cope members being relatively fixed, guides on said fixed member, the other cope member being slidably mounted on said guides, a drag member hinged to the fixed member to swing freely relative thereto, and means for holding said members together to close 100 the mold. 95

7. A permanent mold for making castings, comprising a two-member cope, one of said cope members being fixed and the other cope member being slidable relative to the fixed cope member, means for securing said cope members together, a drag member hinged to said fixed cope member and adapted to swing freely relative to the cope, and means on the slidable cope member and on the drag member for holding the drag member in close relation with the cope members. 105 110

8. A permanent mold for making castings, comprising a cope having a fixed member and a slidable member, a drag hinged at one side to the cope and adapted to swing freely and bodily relative to the cope, means for securing the drag in close position relative to the cope, a keeper on the slidable member of the cope, a tongue on the drag to engage said keeper, and a removable pin to hold said tongue in engagement with the keeper. 115 120

9. A permanent mold for making castings, comprising a two-member cope having a mold cavity therein with the parting line between the two members of the cope extending longitudinally of the mold and substantially centrally through the cavity, one of said cope members being slidable relatively to the other cope member, a drag mem- 125 130

ber, and means for securing said members together for closing the mold.

10. A permanent mold for making castings, comprising a two-member cope having a mold cavity therein, one of said members being slidable relatively to the other member, a drag member hinged to swing relatively to the cope, and means for securing said members together for closing the mold.

11. A metal mold for casting a brake shoe, comprising a two-member cope and a drag member having a mold cavity therein, one of said cope members being slidable relatively to the other cope member and the drag member being movable relatively to the cope, parts of the walls of said cavity in the drag and in the cope having a facing of refractory material and other parts of said walls being left bare so that the metal of the drag and cope will have a chilling effect upon the casting at the bare parts of the walls, but will be prevented from chilling the casting opposite the refractory facing.

12. A mold for casting a brake shoe comprising a two-member cope and a drag having a mold cavity therein, one of said cope members being fixed and the other cope member being slidable relatively to the fixed cope member, the drag member being hinged to the fixed cope member to swing freely relatively thereto, and means for supporting within the cavity the attaching lug and the reinforcing back to be embedded in the shoe casting and the core to form the opening in the lug.

13. A mold for casting a brake shoe, comprising a two-member cope and a drag having a mold cavity therein, the parting line between the two members of the cope extending longitudinally of the mold and substantially centrally through the cavity, and means within the cavity for supporting therein the attaching lug and the reinforcing back to be embedded in the shoe casting and the core to form the opening in the lug.

14. A mold for casting a brake shoe, comprising a two-member cope and a drag having a mold cavity therein, the parting line between the two members of the cope extending longitudinally of the mold and through the cavity, and means within that portion of the cavity in one member of the cope for supporting therein the attaching lug and the reinforcing back to be embedded in the shoe casting and the core to form the opening in the lug while the mold is being closed.

15. A mold for casting a brake shoe, comprising a two-member cope and a drag having a mold cavity therein, the parting line between the two members of the cope extending longitudinally of the mold and substantially centrally through the cavity, and means within the cavity and located partly in one member of the cope and partly in the other member of the cope for supporting the

attaching lug and the reinforcing back to be embedded in the shoe casting and the core to form the opening in the lug during the casting operation.

16. A mold for casting a brake shoe, comprising a two-member cope and a drag having a mold cavity therein with a part of the cavity in one cope member and a part in the other cope member, and means within the part of the cavity in one cope member for supporting therein the attaching lug and the reinforcing back to be embedded in the shoe casting and the core to form the opening in the lug.

17. A mold for casting a brake shoe, comprising a two-member cope and a drag having a mold cavity therein with a part of the cavity in one cope member and a part in the other cope member, the cavity in one cope member being constructed to cooperate with a back unit comprising an attaching lug, a core for forming the opening in the lug, and a reinforcing back to support said unit preliminary to closing the mold.

18. A mold for casting a brake shoe, comprising a two-member cope and a drag having a mold cavity therein, a part of the cavity being formed in one member of the cope and a part in the other member of the cope, a unit comprising an attaching lug, a core to form the opening in the lug, and a reinforcing back, and means in one cope member cooperating with said core to support said unit in said member of the cope preliminary to closing the mold.

19. A mold for casting a brake shoe, comprising a two-member cope and a drag having a mold cavity therein, said cavity comprising a recess with side extensions thereof, a part of said cavity being formed in one member of the cope and a part in the other member of the cope, and a core for forming the opening in the lug of the brake shoe engaged with said extensions in one cope member to support said core preliminary to closing the mold.

20. A mold for casting a brake shoe, comprising a two-member cope having a part of a mold cavity formed in one member and a part in the other member, and means for supporting in the part of the cavity in one member of the cope a core for forming the opening in the attaching lug of the shoe preliminary to closing the mold.

21. A mold for casting a brake shoe, comprising a two-member cope having a part of a mold cavity formed in one member and a part of a mold cavity in the other member, shoulders on said members, and a core to form the opening in the attaching lug of the brake shoe having shoulders to engage the shoulders on the cope for supporting the core preliminary to closing the mold and while the mold is closed.

22. The combination of a mold for casting

a brake shoe, comprising a two-member cope having a part of the mold cavity in one member and a part of the mold cavity in the other member, a back unit comprising an attaching lug, a core to form the opening in the lug, a reinforcing back, means for tying said back to said core, and interengaging means between the walls of the mold cavity and said core to support said back unit in the mold cavity preliminary to and while the mold is closed.

23. The combination of a mold for casting a brake shoe and having a mold cavity therein, a core supported in said cavity for forming the opening in the attaching lug of the shoe, and a reinforcing back suspended from said core.

24. The combination of a mold for casting a brake shoe and having a mold cavity therein, a core supported in said cavity to form the opening in the attaching lug of the shoe, and wire ties securing the reinforcing back to the core and holding said back in proper position in the cavity.

25. 25. The combination of a mold for casting a brake shoe and having a mold cavity there-

in, a core for forming the opening in the attaching lug, interengaging means between the walls of the mold cavity and the core to support the core in the mold cavity, a reinforcing back, and means for suspending the reinforcing back from the core. 30

26. The combination of a mold for casting a brake shoe and having a mold cavity therein, a core for forming the opening in the attaching lug of the shoe, shoulders on the walls of the cavity and cooperating shoulders on the core to support the core in the cavity, a reinforcing back, and means for suspending the reinforcing back from the core. 35 40

27. The combination of a mold for casting a brake shoe and having a mold cavity therein, a core for forming the opening in the attaching lug of the shoe, shoulders at the ends of said core, shoulders on the walls of the mold cavity to be engaged by the shoulders on the ends of the core to support the core in the mold cavity, a reinforcing back, and wire ties connecting the reinforcing back to the core. 45 50

JAMES S. THOMPSON.
